UNITED STATES PATENT OFFICE.

WILLARD H. GILMAN, OF BOSTON, MASSACHUSETTS, ASSIGNOR TO ARTHUR WILLIAM TICE, OF SAME PLACE, AND RICHARD S. DODGE AND RICHARD NAGLE, OF LYNN, MASSACHUSETTS.

CASH-REGISTER.

SPECIFICATION forming part of Letters Patent No. 448,020, dated March 10, 1891.

Application filed April 23, 1890. Serial No. 349,119. (No model.)

To all whom it may concern:

Be it known that I, WILLARD H. GILMAN, of Boston, in the county of Suffolk, State of Massachusetts, have invented certain new and useful Improvements in Cash-Registers, of which the following is a description sufficiently full, clear, and exact to enable any person skilled in the art or science to which said invention appertains to make and use the same, reference being had to the accompanying drawings, forming part of this specification, in which—

Figure 1 is a perspective view of the case, showing the keys; Fig. 2, an end elevation showing the operative mechanism, the end of the case being removed; Fig. 3, a front elevation, the case-front being removed; Fig. 4, a sectional end elevation, and Fig. 5 a view illustrating certain details of construction.

Like letters and figures of reference indicate corresponding parts in the different figures of the drawings.

My invention relates to that class of cash-registers which are provided with an adding mechanism; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the case, which is preferably rectangular in form and is provided with a hinged cover b and lock d therefor. A cash-drawer f is fitted to slide in the bottom of the case. A coiled spring g, disposed between the back of the drawer and back wall of the case, tends to force said drawer outward.

A centrally and horizontally arranged sectional rotary shaft h is journaled in brackets or supports i within the case, the sections being disposed in alignment and adapted to rotate independently. A series of large friction-wheels B C D E F are respectively keyed on the independent shaft-sections h equidistant from each other.

Between succeeding friction-wheels a series

of five pulleys j k l m p are mounted loosely on each shaft-section h, said pulleys being graded in size and provided with two small grooves q r on their peripheries. On the web of each of these pulleys three equidistant retaining-pawl t are pivoted to engage a ratchet-wheel v, (see Fig. 4,) keyed to each shaft-section h.

Five series y z of rods w are fitted to slide longitudinally through the front x of the case, each series consisting of five rods arranged diagonally, as shown in Fig. 1. The outer end of each rod or key w is provided with a knob or head, on which is imprinted a numeral representing the amount each key is adapted to register. The keys in the series y are numbered from 1 to 5, consecutively, beginning with the lowest key and are employed to register amounts in dollars. The keys in the series z are numbered consecutively from 5 to 100, employing each fifth numeral and are used to register the amount of cents.

A vertically-arranged plate H is mounted on the forward or free end of a frame 15, pivoted at 16 to the rear wall of the case. This plate is notched to rest on the rods w, as shown in Fig. 3, and is adapted to swing or play vertically. Each end of the plate H projects downward at 17 beside the ends of the drawer f, and a retaining-pawl 18, (see Fig. 2,) pivoted to the drawer ends, is adapted to engage the inner faces of the arms 17 and lock said drawer against the force of the spring g. An inclined hook-shaped flange or boss 19 is formed on the inner end of each rod w, and a series of inclined hooks 20, (see Fig. 2,) fixed on the plate H, are arranged to respectively engage said bosses as the rods w are drawn outward and prevent the keys from being accidentally pushed inward after registering.

A cord 21, secured to the inner end of each rod w, passes around a pulley j k l m p, to which they are secured in the grooves q. The cords from the lower keys in the series connect with the largest pulleys j, and the succeeding key-cords with the next smaller pulleys, the upper keys or rods bearing the largest numerals of each series being connected with the smallest pulleys p.

A horizontal bar or bracket 22 is secured to

to the back wall of the case, and from said bar a series of spring-rods 23 project under the pulleys. To the outer ends of each of said rods a cord 24 is secured and passes the 5 adjacent pulley in the groove *r* thereof and in a direction opposite to that of the cords 21, the purpose of said springs and cords being to return the pulleys after they are rotated by the key-cords, as hereinafter described.

10 An alarm-bell 1 is mounted on the top 30 of the drawer-case, and a clapper 31 is pivoted in said top in position to strike the bell as the drawer is withdrawn.

15 A series of endless tapes 35 passes over rolls 36 on the front and back of the case, and are respectively disposed in the same vertical plane as the friction-wheels. Each tape is held in engagement with its friction-wheel by the free end of a flat spring 37. The face 20 of the tape is spaced and the spaces thereon numbered consecutively. The spring ends have a slot or opening 38, (see Fig. 5,) through which the numerals on the tape are consecutively displayed.

25 In the use of my improvement, when a sale is made of more than one dollar in amount, the key *w* in the left-hand series *y*, bearing the numeral representing the amount in dollars, is drawn outward. For example, the 30 fifth key or key representing a sale of five dollars is shown in the drawings as withdrawn. The boss 19 on said key engaging the fixed catch 20 on the plate *H* causes said plate to be elevated as the catch passes over 35 the incline of said boss. This frees the pawl 18 on the drawer *f* and permits the spring *g* to throw said drawer outward. The clapper 31, pivoted on the drawer, strikes the bell as the drawer moves. The key when withdrawn, 40 being connected with a small pulley *p*, causes the corresponding shaft-section *h* to rotate a determined distance from right to left, as viewed in Fig. 2, by means of the pawls *t* on said pulley engaging the adjacent ratchet *v* on said shaft. The friction-wheel *B* on said shaft at the same time rotating causes its 45 tape 35 to advance a corresponding distance and expose a numeral through the spring-slot 38 greater by five in amount than the numeral previously exposed through said slot.

50 If it is desired to register an additional amount in cents, a key of one of the series *z* is drawn outward, the operation on its shaft-section being as above described. As said second key is withdrawn, the plate *H* is thereby elevated, freeing the key of the series *y* previously withdrawn from its catch 20. The cord 24 having been wound on the pulley *p* by such withdrawal and its spring 23 there- 55 by distended, as soon as said key is thus released said spring acts at once to rotate said pulley *p* in the opposite direction. This winds the cord 21 on said pulley and draws said key inward again out of position to be engaged by its catch 20. The pawls *t* click in the ratchet and do not interfere with the return rotation. It will be seen that by this ar-

angement of parts some one key *w* is always withdrawn, and that only one key at a time can be withdrawn, said withdrawn key being 70 released and returned by its spring as soon as a new key is moved sufficiently to register. When the drawer is closed, its pawls 18, being pivoted, passes under the arm 17 and again locks it. To obtain the gross amount 75 of sales registered, the amounts exposed on the friction-wheels are added together, that on the wheel *B* indicating dollars and on the remaining wheels different amounts in cents. By connecting the keys indicating the smaller 80 amounts of each series with the larger pulleys on the shaft-sections and those keys representing larger amounts with the smaller pulleys the rotation of said shaft-sections and their respective friction-wheels is thereby 85 regulated for each key and the indicator-tape caused to move a proportionate distance. The tapes 35 may be omitted and the wheels *B C D E* numbered peripherally, if desired. The springs 37 in this case may be employed to 90 indicate the numeral on each wheel to be taken in computing the gross amount. Coiled springs disposed on the shaft-sections may be employed to return the pulleys and the springs 23 and cords 24 dispensed with.

95 Having thus explained my invention, what I claim is—

1. In a cash-register, a case, a series of sliding keys therein, a rotary shaft bearing a friction-wheel and pulleys, respectively connected with said keys, and an indicator-tape in engagement with said wheel and adapted to be moved thereby as the shaft is rotated by the withdrawal of one of said keys, substantially as described.

100 2. In a cash-register, the combination of a case, a sectional shaft mounted therein, graded pulleys arranged in series on each shaft-section, whereby the shaft may be rotated to move the tape as said keys are withdrawn, sliding keys mounted in the case-front and respectively connected with said pulleys, a friction-wheel on each shaft-section, and an indicator-tape in engagement with each wheel, substantially as set forth.

110 3. The combination of a case provided with a spring-actuated money-drawer, a pivoted plate engaging a locking-pawl on said drawer, sliding keys in the case, catches on said plate, and inclined bosses on said keys for engaging said catches and elevating the plate to release said drawer, substantially as set forth.

120 4. The combination of a case, a rotary shaft, a series of graded pulleys mounted loosely thereon, pallets on said pulleys engaging ratchets on said shaft, a series of sliding keys connected with said pulleys and rotating the shaft when withdrawn, spring-actuated cords on said pulleys for returning them when the key is released, a friction-wheel, and a recording-tape, substantially as and for the purpose set forth.

130 5. The combination of a case provided with a spring-actuated money-drawer with a slid-

ing key in said case actuating a drawer-releasing mechanism when withdrawn, a rotary shaft actuated by said key, a friction-wheel on said shaft, and a recording-tape moved by 5 said wheel, substantially as described.

6. In a cash-register, a case, longitudinally-sliding keys mounted in diagonally-arranged series therein, a shaft bearing a friction-wheel and a series of loose graded pulleys 10 connected by cords with said keys, pallets on the pulleys engaging ratchets on the shaft, springs secured to the case and connected by cords with the pulleys, and a recording-tape in engagement with said wheel, substantially 15 as set forth.

7. In a cash-register, the combination of a case, a shaft bearing an indicator-wheel and a series of loose pulleys, sliding keys actuating said pulleys when withdrawn, mechanism 20 for rotating the shaft as the pulleys are moved, and springs for returning said pulleys and keys, substantially as described.

8. In a cash-register, a case, a shaft bearing an indicator-wheel and series of loose pulleys, mechanism for rotating the shaft when the pulleys are moved in one direction, springs for returning the pulleys when released, a spring-actuated money-drawer, a 25 locking mechanism therefor, sliding keys connected with said pulleys and respectively adapted to conjointly rotate said shaft and release said locking mechanism when withdrawn, and catches on said mechanism for independently locking said keys, substantially 30 as described.

35 9. In a cash-register, the case A, provided with the spring-actuated drawer f, in combi-

nation with the sliding keys w, having inclined bosses 19, the hinged plate H, provided with catches 20, and the pawl 18, engaging 40 said plate to lock the drawer, substantially as described.

10. The combination of case provided with a cash-drawer, sliding keys arranged in series and independently actuating a drawer-releasing mechanism when withdrawn, a rotary shaft actuated by said keys, an indicator-wheel, a spaced and numbered tape, an index-finger, catches for locking the keys when withdrawn, and springs for returning them 45 50 when released, substantially as and for the purpose set forth.

11. The combination of the case A, provided with the drawer f, the pivoted plate H for locking said drawer, and the keys w, actuating an indicating mechanism and provided with projections engaging catches on said plate when the keys are withdrawn, substantially 55 as and for the purpose set forth.

12. The combination of the case A, the sectional shaft h, each shaft-section bearing an indicating-wheel and a series of graded loose pulleys, the keys w, arranged in series and connected with said pulleys, mechanism connecting the pulleys and shaft-sections for rotating said sections as the keys are withdrawn, the springs 23 and cords 24 for reciprocating the pulleys, and means for independently locking the keys when drawn outward. 60 65
